(57) **CLAIM**

The ornamental design for a laboratory analyzer, as shown and described.

DESCRIPTION

FIG. 1 is a front perspective view of the laboratory analyzer; FIG. 2 is a top plan view of the FIG. 1 device; FIG. 3 is a front elevation view of the FIG. 1 device; FIG. 4 is a left side elevation view of the FIG. 1 device; FIG. 5 is a right side elevations view of the FIG. 1 device; FIG. 6 is a rear elevation view of the FIG. 1 device; FIG. 7 is a bottom plan view of the FIG. 1 device; FIG. 8 is a rear elevation view of the FIG. 1 device; and, FIG. 9 is a bottom plan view of the FIG. 1 device. FIGS. 6 and 7 show the FIG. 1 device with a series of caps, located on the lower rear portion of the device, in an open condition and FIGS. 8 and 9 show the same device with the caps in a closed condition. The broken lines in FIGS. 1-7 and 9 are for illustrating functional features and form no part of the claimed design.
